TIRE

William Edward Hardeman, Solihull, England,
assignor to Dunlop Tire and Rubber Corpora-
tion, Buffalo, N. Y., a corporation of New York

Application February 27, 1952, Serial No. 18,690

In Great Britain January 11, 1952

Term of patent 14 years

(Cl. D90—20)

To all whom it may concern:

Be it known that I, William Edward Harde-
man, a subject of the King of Great Britain,
residing at Solihull, Warwickshire, England, have
invented a new, original, and ornamental Design
for a Tire, of which the following is a specifica-
tion, reference being had to the accompanying
drawing, forming a part hereof.

Fig. 1 is a perspective view of a tire, show-
ing my new design;

Fig. 2 is a fragmentary perspective view there-
of; and

Fig. 3 is a fragmentary top plan view thereof.

I claim:

The ornamental design for a tire, as shown.

WILLIAM EDWARD HARDEMAN.
